**AUTOMATIC THREAD CUTTING MECHANISM
FOR BUTTON SEWING MACHINES**
Horace E. Owens, Owings, S.C., assignor to Her Majesty
Underwear Company, Mauldin, S.C., a corporation of
South Carolina

Filed Dec. 22, 1965, Ser. No. 515,612
9 Claims. (Cl. 112—252)

This invention relates to a thread cutting mechanism for 10 sewing machines.

The main objective of the invention is to provide a simplified, economical, automatic thread cutting attachment for a certain class of button sewing machines which will cut the thread cleanly upon completion of each button sewing cycle. The mechanism is particularly adaptable to a shank button sewing machine designated Class 175-62 in an instruction booklet for Singer Sewing Machines, 1958 edition, by the Singer Manufacturing Company. The particular button sewing machine is entirely conventional and is well-known in the art.

Another object of the invention is to provide an automatic thread cutting attachment for the above class of machine which takes advantage of the movement of the sewing machine stop motion for directly controlling the cycle of operation of the invention. This greatly simplifies the invention mechanism and renders it substantially fool-proof in its timing and automatic cycle of operation and results in the minimum possible number of parts for the actual attachment.

Still another object is to provide an automatic thread cutting attachment which is rugged and durable and which requires no alteration of the basic sewing machine structure or repositioning of its operating components and no interference with the button sewing cycle of operation.

Other objects and advantages of the invention will become apparent during the course of the following detailed description.

In the accompanying drawings forming a part of this application and in which like numerals are employed to designate like parts throughout the same,

FIGURE 1 is a fragmentary plan view of a shank button sewing machine, partly in cross section, having the invention thread cutting mechanism mounted thereon in one operative position;

FIGURE 2 is a similar view showing the thread cutting mechanism in the active or cutting position;

FIGURE 3 is an enlarged fragmentary side elevational view of the thread cutting mechanism;

FIGURE 4 is an enlarged fragmentary end elevation, partly in section, of the sewing machine and invention mechanism showing the relative position of parts at the completion of a button sewing cycle;

FIGURE 5 is a similar view of the same parts at the beginning of the button sewing cycle; and

FIGURE 6 is a fragmentary vertical section taken on line 6—6 of FIGURE 2.

In the drawings, wherein for the purpose of illustration is shown a preferred embodiment of the invention, the numeral 10 designates generally a conventional shank button sewing machine of the type known in the art as a Singer Model No. 175-62 machine. This machine includes a work surface or plate 11 over which the cloth, not shown, is positioned to have shank buttons 12 sewn thereon by the well-known zig-zag needle mechanism. The shank buttons are positioned on edge, as shown in FIGURE 1, in a special anvil or support 13 for this purpose, also of a known, conventional construction.

The sewing machine has a main drive shaft 14 upon which is mounted a stop dog 15 which operates in conjunction with a cushion spring holder 16 mounted on a

2

machine rock shaft 17 and carrying a stop dog cushioning spring 18 projecting therefrom as shown in the drawings. The elements 16, 17 and 18, along with the stop dog 15, are all conventional parts of the machine stop motion which are cycled and operated automatically.

The automatic thread cutting mechanism forming the direct subject matter of the invention comprises an elongated bar 19 having a longitudinal groove 20 in its top face and serving as a fixed bed or guide for an elongated carriage member 21 which engages slidably within the groove 20 and extends for its entire length. The bar 19 which forms the supporting body portion of the mechanism is attached to one side of the machine base 22 by screws 23 or the like at spaced points. The carriage member 21 which is in effect a slide includes a forward laterally enlarged head portion 24 integral therewith having shoulders 25 adapted to engage the forward end of the bar 19 so as to positively limit the rearward movement of the carriage member. The carriage member 21 is resiliently biased in a retracted or inactive position, as shown in FIGURE 1, by a carriage return spring 26 having its forward end anchored at 27 to the carriage member and its rear end similarly anchored at 28 to a bracket 29 fixedly secured at 30 to the rear portion of bar 19. In addition to anchoring the spring 26, the stationary bracket 29 aids in retaining the carriage member or slide 21 in the shallow groove 20. A further retainer plate 31 is provided for this purpose on the bar 19 near the forward end of the same. The bracket 29 also limits the forward movement of carriage member 21 by contact with an upstanding rigid lug 32 formed integrally on the rear end thereof. In normal operation for thread cutting, the extent of forward movement of the carriage member 21 is such that the lug 32 does not quite make contact with the bracket 29. Nevertheless, this bracket would restrict excessive forward movement of the carriage member.

The forward head 24 is provided with a longitudinal slot 33, allowing the adjustable connection of a horizontal extension arm 34 to the carriage member 21, as indicated at 35. The extension arm 34 projects laterally of the carriage member and closely overlies the machine work surface 11. The extension arm 34 is thus mounted bodily upon the carriage member 21 and reciprocates therewith.

A reciprocatory thread cutting blade or knife 36 operates slidably upon the anvil surface 13 beneath a grooved hold-down and guide element 37 fixedly secured to the member 13. The leading end 38 of blade 36 is suitably beveled to form a thread cutting edge. The blade is adapted to operate beneath the cloth, not shown, to cut off the thread cleanly close to the button shank 39 after the sewing operation is completed. The rear end of blade 36 carries an upstanding pin 40 which is received by a slot 41 in the extension arm 34 so that the latter may drive the blade 36 smoothly and without binding. It will be understood that the elements 21, 34 and 36 reciprocate as a unit and have rectilinear motion imparted thereto along the guide slot 20.

Fixedly anchored within an opening 42 in the rear end 60 of bar 19 is a pin or shaft 43 held in place by a set screw 44 or the like. The shaft 43 projects for a considerable distance beyond the rear end of the bar 19 and has a depending positioner arm 45 rigidly secured thereto as by a set screw 46. The elements 43 and 45 are therefore both 65 rigid with the stationary bar 19.

Between the positioner arm 45 and the rear end of bar 19 a sleeve 47 is rotatably mounted upon the shaft 43, and this sleeve directly carries a plunger guide 48 which may be integral therewith or welded thereto. The plunger guide 48 is on the top of sleeve 47, as shown, and projects laterally beyond the inner side thereof and across the back of the machine base 22, FIGURE 4. A block-

like cam actuator 49 is arranged within a recessed portion of the plunger guide 48 and is pivoted thereto for horizontal turning movement thereon by a suitable pivot element 50 arranged near one corner of the cam actuator. As shown in FIGURES 1 and 2, the cam actuator 49 is square and when it is in the inactive position, FIGURE 1, one of its straight sides 51 abuts the edge of the recess in which the actuator is seated so that it will turn no further in the counter-clockwise direction, as viewed in FIGURE 1. The cam actuator 49 is resiliently biased to this inactive position by a return spring 52 having one of its ends anchored to the cam actuator and its other end similarly anchored to the plunger guide 48.

The forward edge 53 of the cam actuator 49 which directly engages the lug 32 of carriage member 21 is normally spaced slightly therefrom while in the inactive position, as indicated at 54 in FIGURE 3. The cam actuator 49 is caused to turn to the active position in FIGURE 2 by a plunger 55 mounted slidably within a bore of the plunger guide 48 and having its leading end directly contacting the edge 51 of the cam actuator 49. The pin element 56, FIGURE 6, which serves to anchor the spring 52 to the guide 48, may also pass through a notch 57 formed in the plunger 55, so as to limit positively the reciprocatory movement of the plunger upon the guide 48.

It may now be understood that the entire guide 48, plunger 55 and cam actuator 49 are all bodily mounted upon and turnable with the sleeve 47 upon the axis of shaft 43. The freely rotatably plunger guide 48 and associated elements rests freely upon and is supported by the cushion spring holder 16, as best shown in FIGURE 4, and this constitutes an important feature of the invention and its operation, to be further described. A diagonal positioner spring 58 interconnecting the guide 48 and the positioner arm 45, as shown at 59, serves to resiliently hold the guide in firm contact with the spring holder 16 at all times. When the spring holder 16 turns in either direction with the rocker shaft 17, the plunger guide 48 and associated elements will turn automatically therewith, and the spring 58 will maintain contact between the parts 48 and 16, as shown.

The cycle of operation of the thread cutting mechanism above-described in conjunction with the sewing machine stop motion is as follows:

When the sewing machine is engaged in a conventional manner to begin the button sewing cycle, the machine stop dog cushioning spring holder 16 automatically rotates away from the revolving stop dog 15 which turns with the main drive shaft 14. This situation is shown in FIGURE 5. When this occurs, the holder 16 will lift and carry the plunger guide 48, plunger 55 and all associated parts away from the stop dog and out of its path of rotation during the sewing of the button onto the cloth.

As the normal sewing cycle is completed, the cushion spring holder 16 will return automatically to its active machine stopping position shown in FIGURE 4 and this is conventional in the sewing machine. This allows the positioner spring 58 to pull the plunger guide 48 down to the active approximately level position shown in FIGURE 4. At this time, both the plunger 55 and the cushion spring 18 are in the path of movement of the rotating stop dog 15.

As the stop dog 15 moves into the stop position and slightly short thereof, it contacts plunger 55, FIGURE 4, causing the plunger to shift axially toward the cam actuator 49 and turning the cam actuator, as shown in FIGURE 2, to cause shifting of the carriage member 21 and blade 36 to the thread severing position where the thread is cleanly severed close to the button shank.

The plunger 55 absorbs the initial impact of stop dog 15 and actually aids in stopping the machine. However, continued slight movement of the stop dog after engag-

ing the plunger brings the stop dog into contact with the cushioning spring 18 and completes the stopping of the shaft 14 and the machine. Following this, the compressed spring 18 expands to its relaxed position and 5 normal length pushing back the stop dog 15 slightly and allowing the cam actuator 49 to return to the inactive position in FIGURE 1 under influence of the spring 52. This also moves the plunger 55 to its retracted or inactive position. At this time, the carriage return spring 26 10 automatically withdraws cutting blade 36 from the thread and returns the blade, arm 34 and carriage member 21 to the fully retracted position, thus completing the sewing and thread cutting cycle and preconditioning the parts for the next cycle of operation, where the holder 15 again moves the guide 48 and associated elements 15 clear of the path of movement of the dog 15, as the machine starts up.

It is now clear that a highly simplified positive acting automatic thread cutter has been provided on the shank 20 button sewing machine which is operated directly by the machine stop motion in such a manner that the thread is cut at precisely the right time, namely, at the end of the cutting cycle. Also, the mechanism in conjunction with the stop motion conditions itself automatically for 25 each succeeding cycle of operation, as explained.

It is to be understood that the form of the invention herewith shown and described is to be taken as a preferred example of the same, and that various changes 30 in the shape, size and arrangement of parts may be resorted to, without departing from the spirit of the invention or scope of the subjoined claims.

I claim:

1. A thread cutting mechanism for a button sewing 35 machine of the class having a rotating stop dog and a coacting cushioning part movable cyclically into the path of travel of the stop dog and clear of such path of travel, said mechanism comprising a supporting body portion attachable to the body of the sewing machine, a thread 40 cutter device movably engaging said body portion and shiftable thereon toward and away from thread cutting positions, and an actuator means for the thread cutter device movably mounted upon the supporting body portion and being engaged with and supported by said cushioning part and shiftable with such part cyclically into the path of travel of the stop dog so that the stop dog may directly engage said actuator means and operate said cutter device to cut the button sewing thread.

2. The invention as defined by claim 1, and wherein 50 said cutter device is a reciprocating cutter on the supporting body portion and said actuator means comprises a member pivoted to the body portion and adapted to rest upon the cushioning part, a plunger having guided engagement with said member and adapted to be engaged directly by said dog, and a pivoted cam actuator 55 carried by said member and movable bodily therewith and adapted to engage said reciprocating cutter.

3. A thread cutting mechanism for a button sewing 60 machine of the class having a rotating machine stop dog and a coacting stop part which swings cyclically into the path of movement of the stop dog and clear of said path of movement, said mechanism comprising a guiding and supporting member adapted to be rigidly secured to one side of the sewing machine base, a reciprocatory slide on said member, resilient means biasing said slide to a retracted position, a thread cutter element carried by the slide and positioned for direct engagement with the thread to cut the thread when the slide is extended on 65 said guiding and supporting member, a plunger guide body pivotally mounted upon one end of the guiding and supporting member and adapted to contact and rest upon said coacting stop part and to swing therewith, resilient means connected with the plunger guide body and holding it in contact with the coacting stop part, a reciprocating plunger on said guide body and adapted to direct 70

ly engage said stop dog when in the path of movement thereof, a pivoted actuator part on the guide body and shiftable by said plunger against said slide to move the same in a thread cutting direction, and resilient means connected with said actuator part and urging the same toward an inactive position with said plunger.

4. The invention as defined by claim 3, and wherein said guiding and supporting member is an elongated bar having a longitudinal groove, said slide engaging within said groove and extending longitudinally therethrough, a lateral extension arm on the forward end of said slide, and said thread cutter element offset from said slide and connected with said extension arm.

5. The invention as defined by claim 3, and a shaft extension on the rear end of the guiding and supporting member, a sleeve rotatably mounted on the shaft extension and bodily carrying said plunger guide body, a depending member on the shaft extension, and a retractile spring interconnecting the depending member and said plunger guide body to hold the same in contact with said coacting stop part and allowing the plunger guide body to swing with the coacting stop part.

6. The invention as defined by claim 3, and wherein said pivoted actuator part is a block-like element on the top of the plunger guide body, said guide body having a recess receiving said actuator part, and a lug on said reciprocatory slide positioned for engagement with one edge of the actuator part when the same is turned by said plunger.

7. In a button sewing machine of the class having a rotating stop dog and a coacting pivoted stop part which swings cyclically into the path of movement of the stop

dog and clear of said path, the combination with said coacting stop part of a pivoted guide device on said machine resting upon and supported by the coacting stop part, resilient means holding the guide device in contact with the coacting stop part, movable actuator means on said guide device adapted to be operated by the stop dog when said coacting stop part swings into the path of movement of the stop dog, and movable thread cutter means on said machine operated by said actuator means in response to operation thereof by the stop dog immediately prior to the stopping of the machine by engagement of the stop dog with the coacting stop part.

8. The invention as defined by claim 7, and wherein the coacting stop part includes a cushioning spring for the stop dog and said actuator means includes a plunger extending slightly in advance of the cushioning spring to engage with the stop dog prior to engagement of the dog with said spring.

9. The invention as defined by claim 7, and a common support member on said machine for the thread cutter means and pivoted guide device.
